US00D806057S

(12) **United States Design Patent** (10) Patent No.: **US D806,057 S**
(45) Date of Patent: **** Dec. 26, 2017**

(54) **SET-TOP-BOX RECESS FOR PORTS**

(71) Applicant: **OpenTV, Inc.**, San Francisco, CA (US)

(72) Inventors: **Joonyoung Park**, Mountain View, CA (US); **Jihyun Park**, Mountain View, CA (US)

(73) Assignee: **OpenTV, Inc.**, San Francisco, CA (US)

(**) Term: **15 Years**

(21) Appl. No.: **29/549,156**

(22) Filed: **Dec. 18, 2015**

(51) LOC (10) Cl. **14-03**

(52) U.S. Cl.

USPC **D14/217**

(57) **CLAIM**

The ornamental design for a set-top-box recess for ports, as shown and described.

DESCRIPTION

FIG. 1 is a perspective view of a set-top-box recess for ports showing our new design.

FIG. 2 is a rear perspective view thereof.

FIG. 3 is a front view thereof.

FIG. 4 is a rear view thereof.

FIG. 5 is a side view thereof.

FIG. 6 is a side view thereof.

FIG. 7 is a top view thereof; and,

FIG. 8 is a bottom view thereof.

The broken line in the drawings represent unclaimed environment only and forms no part of the claimed design.

1 Claim, 6 Drawing Sheets
